UNITED STATES PATENT OFFICE.

JAMES L. HEELEY, OF ATTLEBOROUGH FALLS, MASSACHUSETTS.

DESIGN FOR AN ORNAMENTAL CHAIN-LINK.

SPECIFICATION forming part of Design No. 12,940, dated May 23, 1882.

Application filed April 22, 1880. Term of patent 7 years.

To all whom it may concern:

Be it known that I, JAMES L. HEELEY, a citizen of the United States, residing at Attleborough Falls, in the county of Bristol and State of Massachusetts, have invented and produced a new and original Design for Ornamental Chain-Links, of which the following is a specification, reference being had to the accompanying drawings, forming part thereof.

The nature of this design is fully represented in the accompanying drawings, in which Figure 1 shows a link in perspective view containing the same. Fig. 2 shows a modification thereof.

Similar letters indicate corresponding parts. The letter A designates a box constituting the essential feature of the link. This box has a polygonal cross-section, and in the angles thereof are notches b, while in its sides are parallel slots c, extending lengthwise of the arti-

cle. In some cases the notches b are arranged near the opposite ends of the box A and the slots c intermediate thereof, as shown in Fig. 1, while in others the notches are made to alternate with the slots, as, for example, shown in Fig. 2.

What I claim as new, and desire to secure by Letters Patent, is—

The design for an ornamental chain-link, consisting of a box having notches in the angles thereof, and having longitudinal slots in its sides, as described, and shown in the accompanying drawings.

In testimony whereof I have hereunto set my hand and seal in the presence of two subscribing witnesses.

JAMES L. HEELEY. [L. S.]
